UNITED STATES PATENT OFFICE.

ARTHUR H. BLACKBURN, OF MATTEAWAN, NEW YORK.

AUTOMATIC LATHE FOR WORKING PIPES OR BARS.

No. 846,000.

Specification of Letters Patent.

Patented March 5, 1907.

Application filed December 23, 1903. Serial No. 186,290.

To all whom it may concern:

Be it known that I, ARTHUR H. BLACKBURN, a subject of the King of Great Britain, residing at Matteawan, in the county of Dutchess and State of New York, have invented certain new and useful Improvements in Automatic Lathes for Working Pipes or Bars, of which the following is a specification, reference being had to the drawing accompanying and forming part of the same.

The object of my present invention is to provide a machine for machining the ends of a pipe or bar which shall be automatic in its operation after the object to be worked has been placed in the machine.

In the embodiment herein specifically shown the apparatus is designed to turn both ends of the object down to any predetermined size simultaneously and to cut off both ends, whereby the pipes or bars will be delivered all of the same length and finish.

The invention itself, however, consists in the novel features and combinations herein-after described, and more particularly pointed out in the claims.

Referring to the accompanying drawings, Figure 1 shows the machine in side elevation. Fig. 2 is a plan view of the same with the work-holding devices in section. Fig. 3 is a view in elevation of the side opposite to that of Fig. 1, showing part of the machine in detail. Figs. 4 and 5 are sections on lines IV IV and V V, respectively, of Fig. 3 looking in the directions of the arrows. Figs. 6, 7, 8, and 9 are detail views of certain parts of the mechanism.

The object to be worked, which in the present instance is shown to be a pipe, is indicated by 1. It is held in a carrier consisting of sleeves 2 3, Fig. 2, mounted to rotate in suitable bearings, as 4 5. Each sleeve carries a chuck 6 7, preferably of the self-centering type, so that the pipe is firmly held at each end. The carrier is rotated through the gear 8 by engagement with a pinion 9 on the counter-shaft, which carries a gear 10, driven by the pinion 11 on the power-shaft 12, having a driving-pulley 13.

The turning-tools 14 15 and the cutting-off tools 16 17, Fig. 2, are held in suitable holders, as shown, mounted over the rock-shafts 18 19. The transverse motion of the tools to cause them to bear on the pipe is effected by means of gear-arms, as 20 21, on the rock-shafts, which engage racks, as 22 23 on the tool-slides. Obviously, if the rock-shafts be

oscillated the tools will be carried inward against the work. To rock the shafts, I provide the shaft 18 with an arm 24 and shaft 19 with an arm 25, having studs 26 27 working in cams 28 29, from which it will be seen that rotation of the latter will rock the shafts 18 19.

A scraper, as 17^a, Fig. 4, may also be provided, in connection with each cutting-off tool, on the tool-carriers, as shown, so as to bear on the pipe, after the end has been cut off, to give the same a final finish or to remove any irregularities which may be left by the turning-tools 14 15.

To reciprocate the turning-tools lengthwise of the work, I provide drums 30 31, preferably located between the first-mentioned cams, as shown, having spiral cam-grooves in which work studs 32 33 on cross-heads 34 35, connected to links 36 37, which are in turn connected to the tool-carriers 38 39, so that rotation of the cam-drums will move the tools 14 15 in the desired manner.

The cams are rotated by engagement of the gear 40 with a worm 41 on a shaft 42, which has a gear 43, driven by a gear 44, which latter is driven by gears 45 46. Gear 46 is carried by a counter-shaft 47, having a sprocket-wheel 48, connected by a chain 85 passing under an idler 49 on the rock-shaft 18 to a sprocket 50, rotatably mounted on the power-shaft 12. The sprocket 50 abuts against the hub 51 of the driving-pulley 13. Both sprocket and hub have holes corresponding to the pins 52, which are rotatably carried by a spring-actuated push-bar 53, so that when the latter is pushed in the pins will be carried into the openings in the pulley-hub and so connect the sprocket 50 rigidly therewith. In this position the bar is engaged and held by a sliding latch 54. The sprocket is thus rotated and drives the cams which reciprocate the tool-slides. If the latch 54 is disengaged from the bar, the latter is instantly retracted by the spring 55 and the sprocket 50, no longer connected with the power-pulley, ceases to be rotated.

It may sometimes happen that by reason of wear or the tools becoming loosened the pipe may not be reduced to the proper size or not entirely cut through by the cutting-off tool, or both, when the operation of the machine is completed, and it is therefore necessary to rework the pipe. In order to bring the tools back to the starting-point quickly, I provide manually-operated means for shift-

ing the same to any position. A convenient method for this purpose is to adapt an end 56 of shaft 42 to be engaged by a crank, (not shown,) and in order to permit manual rotation of the shaft 42, and with it the cams, I mount the mechanism which drives the shaft in such a manner that the two may be disengaged at will. For example, as shown in Figs. 3, 6, and 7, the hanger 57, in which rotates the arbor carrying gears 44 and 45, is revolvably mounted on the shaft 47 in the brackets 58 59, so that it can drop down to the position shown in dotted lines in Fig. 7, carrying the gear 44 out of engagement with the gear 43. The shaft 42 may then be rapidly revolved by means of the crank, causing the tools to move quickly to any desired position. To hold the hanger 57 in raised position, so that the gears 43 and 44 will be in mesh, an arm 60 is provided on the hanger, carrying a pivoted stop 61, Fig. 7, which holds the arm 60 in the vertical position shown and the gears therefore in mesh; but by swinging the stop 61 downward or upward the arm can tilt forward and so disengage the gears.

The operation of the machine will be readily understood from the foregoing. It automatically dresses the ends of the pipe 30 or bar and automatically cuts off a portion, leaving the pipe or bar the desired length and its ends of the desired diameter. The timing of the operations relative to each other depends, of course, upon the arrangement of 35 the cams relative to each other, so that by properly arranging them the operations may occur in succession or simultaneously.

The extent of the operations—that is, the extent of movement, of the tools—depends 40 upon the proportions of the cams and other operative parts, and these also may be varied to any desired degree without departing from the spirit of the invention.

It should be further understood that the 45 machine herein specifically shown and described is only one of the many embodiments of which the invention is capable.

What I claim is—

1. In a machine of the kind described, the 50 combination with means for holding a pipe with the end thereof exposed, and means for rotating the said pipe-holding means, of tool-carriers arranged adjacent to the positions occupied by the exposed ends of the pipe and 55 adapted to be reciprocated longitudinally thereof, a cam-shaft parallel with the said pipe-holding means, cam devices on the shaft, located between the ends of the pipe-holding

means, said cam devices having a pair of peripheral cam-grooves, cross-heads adjacent to the cam devices, having studs engaging the peripheral grooves therein, and links connecting the cross-heads with the respective tool-carriers, whereby the rotation of the cam devices will reciprocate the tool-carriers substantially as described and for the purposes set forth.

2. In a machine of the kind described, the combination with means for holding a pipe with the ends thereof exposed, and means for 70 rotating the said pipe-holding means, of a rock-shaft on each side of the pipe-holding means and parallel therewith, tool-carriers mounted to reciprocate on one of the rock-shafts and located adjacent to the positions 75 occupied by the exposed ends of the pipe, a cam-shaft parallel with the rock-shafts, cam devices on the cam-shaft, located between the ends of the pipe-holding means, having both peripheral and face cam-grooves, cross-heads adjacent to the cam devices and having studs engaging the said peripheral grooves, links connecting the cross-heads with the reciprocating tool-carriers, a second 80 pair of tool-carriers mounted on the other rock-shaft adjacent to the exposed ends of the pipe, and means actuated by the face-grooves on the cam devices for rocking both shafts toward and away from the pipe ends, as set forth.

3. In a machine of the kind described, the combination with means for holding a pipe with the ends thereof exposed, and means for 90 rotating the said pipe-holding means, of a rock-shaft on each side of the pipe-holding means and parallel therewith, tool-carriers mounted to reciprocate on one of the rock-shafts and located adjacent to the exposed 95 ends of the pipe, a cam-shaft parallel with the rock-shafts, cam devices on the cam-shaft, located between the ends of the pipe-holding means, having peripheral and face cam-grooves, cross-heads adjacent to the cam devices and having studs engaging the peripheral grooves, links connecting the cross-heads with the reciprocating tool-carriers, a second 100 pair of tool-carriers mounted on the other rock-shaft adjacent to the exposed ends of the pipe, and arms rigidly mounted on the rock-shafts and having studs engaging the face-grooves on the cam devices, as set forth.

ARTHUR H. BLACKBURN.
